UNITED STATES PATENT OFFICE.

ISAAC W. LITCHFIELD, OF NEWTONVILLE, MASSACHUSETTS.

WRENCH.

1,345,202.

Specification of Letters Patent. Patented June 29, 1920.

Application filed June 17, 1919. Serial No. 304,809.

To all whom it may concern:

Be it known that I, ISAAC W. LITCHFIELD, a citizen of the United States of America, and a resident of Newtonville, Massachusetts, have invented a new and useful Improvement in Wrenches, which invention is fully set forth in the following specification.

This invention relates to wrenches, and more particularly to a wrench having relatively movable jaws which may be moved into operative position and gripped therein by continued relative movement of the jaw-operating members.

An object of this invention is to provide a wrench having relatively movable jaw members and relatively movable operating members therefor with means whereby one continued movement, relatively to each other, of said operating members is effective to move said jaw members into operative position and grip the same therein.

It has heretofore been proposed to provide a wrench comprising relatively movable jaw members with a wedge for gripping one of said jaw members in its operative position. All devices of this type of which I am aware have been seriously defective and inconvenient in that they have required two distinct movements to move the jaw members into operative position and to grip the same therein, *i. e.* they have required one movement to position the jaws operatively to an object and a second movement to effect the movement of the wedge to grip the related jaw in said position. It is an object of this invention to provide a wrench comprising relatively movable jaws and relatively movable operating members therefor with a wedge for gripping one of said jaws in its operative position whereby continued relative movement of the operating members in the same direction will first move the jaws into operative position and then actuate the wedge to grip the related jaw in said position.

Another object of this invention is to provide a wrench comprising relatively movable jaws and relatively movable operating members therefor so related that the wrench may be manipulated by one hand only to both move the jaws into operative position and grip the same therein.

Yet another object of this invention is to provide a wrench which may be conveniently converted into pliers.

Other objects of this invention relate to

the provision of a wrench which is simple in construction, inexpensive to manufacture and convenient and flexible in use.

Stated broadly, the wrench of the present invention comprises relatively movable jaw members, relatively movable hand-operated members for moving said jaw members into operative position, and means, preferably in the form of a wedge, between one of said jaw members and its operating member for gripping the related jaw member in operative position, whereby one continued movement of said operating members relatively to each other is effective to first move said jaw members into operative position and thereafter grip the related jaw member in said position.

The invention is capable of receiving a variety of mechanical expressions, one of which is shown on the accompanying drawing, but it is to be expressly understood that the drawing is for purposes of illustration only and is not to be construed as a definition of the limits of the invention, reference being had to the appended claims for that purpose.

In the drawings,

Figure 1 is a plan of a wrench embodying the present invention.

85

Fig. 2 is a side view thereof.

Fig. 3 is a plan showing the jaws in operative position, and

Fig. 4 is a plan showing means whereby the wrench may be readily converted into pliers.

Referring in detail to the drawing, where-in the same characters of reference are employed to designate corresponding parts in the several figures, the form shown comprises a primary member 1 provided adjacent one end thereof with a hand-grip portion 2 and at the opposite end thereof with a head 3 shaped to constitute a jaw 4 and to provide a slideway 5 and a ledge 6. Movable on the slideway 5 is a rectilinearly-movable jaw 7. Jaw 7 may be constructed in any suitable way for convenient assembly on said slideway and to prevent accidental displacement of said jaw therefrom. In the form shown said slideway is cut to provide a ledge at 8 and the jaw is provided with a depending flange 9, working in the space above said ledge, and a portion 10 underlying said slideway and working in the space between said slideway and the ledge 6.

The lower face of movable jaw 7 is in-

clined as shown at 11, and coöperating with the inclined face of said movable jaw is a wedge 12 having its upper face correspondingly inclined. The coacting faces of said 5 movable jaw and said wedge are preferably plane, but may be roughened, serrated or otherwise suitably constructed to increase the gripping action therebetween, if desired. The angle of inclination of the coacting 10 faces of said movable jaw and wedge is such as to effectively grip and retain the movable jaw member in operative position when, following engagement of said jaw members with an object, the wedge is given a further 15 movement toward the head 3.

In order that the movable jaw member and the wedge shall normally move together, means are provided on one of said 20 elements for engaging and normally moving the other of said elements therewith. In the form shown, yieldable means, desirably in the form of a leaf spring 13, is suitably mounted on the wedge 12, as by a screw 14, and has a protruding end which engages 25 the movable jaw 7. Any suitable expedient may be employed for preventing displacement of said spring; in the form shown a kerf is provided in the wedge and the end of the spring is bent and inserted therein. 30 Movement of the wedge toward the head 3 effects movement of jaw 7 in the same direction but, owing to the yieldable nature of the member 13, the wedge may move relatively to said jaw to grip the latter in operative position. In order that a return movement of the wedge may also retract the jaw, any suitable means may be provided; in the form shown, a pin 15 is mounted in the wedge 12 in position to engage 35 the end of jaw 7 and move the same therewith away from the head 3.

For operating said wedge and movable jaw a lever 16 is suitably fulcrumed on the primary member 1, as by a pivot screw 17, 45 and operatively connected to the wedge 12, as by a pivot screw 18. As the wedge in its movement to and fro slides on the ledge 6 in a rectilinear path, play must be provided between said lever and one of said 50 pivots. In the form shown, the slot 19 through which the pivot screw 17 passes is elongated to provide longitudinal movement of said lever on said pivot.

Any suitable means may be provided for 55 normally urging the operating members apart. In the form shown, a coil spring 20 is positioned between the hand-grip portion 2 of primary member 1 and the hand-grip portion 21 of lever 16, and is retained in 60 position in any suitable way as by engagement with pins 22 projecting from said primary member and said lever.

In accordance with the present invention, 65 means may also be provided whereby the wrench as heretofore described may be

readily converted into pliers. To this end suitable means may be provided for locking movable jaw 7 to the wedge 12. In the form shown, a bolt 23 is mounted in an aperture in said wedge and is movable into and out 70 of the same, being adapted in the latter position to project into a notch 24 in the lower face of jaw 7. Any suitable means may be provided for moving the bolt into and out of its locking position; in the form shown 75 the screw 14 by which the spring 13 is attached to the jaw 12 is threaded into said bolt and may move therewith in an elongated slot 25 in the wedge and spring. In this construction the spring 13 also operates 80 to retain said locking bolt in either of its adjusted positions.

The wrench, therefore, is composed of crossed-members, pivoted at their point of crossing, which have hand-grip portions so 85 related that the wrench may be readily held in and manipulated by one hand. When the hand-grip portions 2 and 21 are forced toward one another the lever 16 slides the wedge 12 along the ledge 6, the lever sliding 90 on its pivot 17, owing to the elongated slot 19, to compensate for the rectilinear movement of said wedge. The wedge carries the movable jaw 7 therewith owing to the spring 13, but when the jaws 4 and 7 engage an 95 object so that their further relative movement is prevented wedge 12 may move relatively to jaw 7, owing to the slight clearance therebetween and the yieldable nature of spring 13, to urge said jaw transversely to 100 its first direction of movement, by wedging said jaw against its way 5, and thereby firmly grip the same in operative position. When the pressure on the hand-grip portions 2 and 21 is relieved, the spring 20, 105 tensioned by the previous movement of said hand-grip portions, returns the lever 16 and wedge 12 to initial position, the pin 15 on said wedge carrying the jaw 7 to initial 110 position.

Furthermore, if the locking-bolt 23 be provided, the wrench may be readily converted into parallel pliers by locking the jaw 7 to the wedge 12.

It will therefore be perceived that a simple, inexpensive and readily manipulated wrench has been provided which may be conveniently operated by one hand and which, by one continued relative movement of the hand-operated members, moves the 115 jaws into operative position and thereafter grips the same in said position.

While the embodiment of the invention illustrated on the drawing has been described with considerable particularity, it 120 is to be expressly understood that the invention is not limited thereto for the same is capable of receiving a variety of mechanical expressions some of which will readily suggest themselves to those skilled in the 125 130

art. Reference is therefore to be had to the appended claims for a definition of the limits of the invention.

What is claimed is:

- 5 1. A wrench comprising relatively-movable hand-operated members, relatively-movable jaws and means whereby said jaws are moved into operative position by relative movement of said first-named members, said means comprising a wedge between one of said jaws and its operating member which becomes effective after said jaws are in operative position to grip the related jaw in said position upon continued 10 relative movement of said first-named members.
2. A wrench comprising a pair of crossed hand-operated members pivotally connected at the point of crossing, relatively-movable 20 jaws and means whereby said jaws are moved into operative position by relative movement of said hand-operated members, said means comprising a wedge between one of said jaws and its operating member, becoming effective after the jaws are in operative position and operated by continued relative movement of said hand-operated members, for gripping the related jaw in operative position.
3. A wrench comprising a primary member provided with a jaw, a second jaw, and means for moving said second jaw into operative position comprising a lever fulcrumed on said primary member, and a wedge between said lever and second jaw, becoming effective after the jaws are in operative position and operated by continued movement of said lever, for gripping the related jaw in said position.
4. A wrench comprising a primary member provided with a jaw and a slideway, a rectilineally-movable jaw slidable on said way, and means for moving said slideway into operative position comprising a lever fulcrumed on said primary member and a wedge operated by continued movement of said lever for forcing said jaw against said way to grip said jaw in said position.
5. A wrench comprising a primary member provided with a jaw, a second jaw movable on said primary member, a wedge movable on said primary member and coacting with said movable jaw, a lever fulcrumed on said primary member and operatively connected to said wedge, and means between said movable jaw and wedge whereby said lever may first move said jaw and wedge together into operative position and then move said wedge relatively to said jaw to grip the latter in said position.
6. A wrench comprising a primary member provided with a jaw and having a hand-grip portion, a second jaw movable on said primary member, a wedge movable on said

primary member and coacting with said movable jaw, a lever operatively connected to said wedge and fulcrumed on said primary member, said lever having a hand-grip portion adjacent said first-mentioned hand-grip portion whereby said lever and member may be manipulated by one hand, and means between said movable jaw and wedge whereby said levers may move said jaw and wedge together into operative position and thereupon move said wedge relatively to said jaw to grip the same in said position.

7. A wrench comprising a primary member provided with a jaw, a second jaw movable on said primary member, a wedge movable on said primary member and having means for normally moving said movable jaw therewith, and a lever fulcrumed on said primary member and operatively connected to said wedge to first position said movable jaw in operative position and then move said wedge relatively to said jaw to grip the latter in said position.

8. A wrench comprising a primary member provided with a jaw, a second jaw movable on said primary member, a wedge movable on said primary member and having yieldable means engaging said movable jaw for moving said jaw with said wedge toward operative position, and a lever operatively connected to said wedge and fulcrumed on said primary member for moving said movable jaw to operative position and said wedge relatively to said jaw to grip the same in said position.

9. A wrench comprising a primary member provided with a jaw, a second jaw movable on said primary member, a wedge movable on said primary member and having means for moving said jaw with said wedge toward operative position and for retracting said jaw with said wedge, and a lever operatively connected to said wedge and fulcrumed on said primary member for moving said jaw into and out of operative position and said wedge relatively to said jaw to grip and ungrasp the same.

10. A wrench comprising a primary member provided with a jaw, a second jaw movable on said primary member, a wedge movable on said primary member and coacting with said movable jaw, a lever operatively connected to said wedge, means between said wedge and movable jaw whereby said lever may move said jaw and wedge together into operative position and said wedge relatively to said jaw to grip the same in said position, means comprising a spring between said primary member and lever for normally moving said jaws apart.

11. A wrench comprising a primary member provided with a jaw, a second jaw movable on said primary member, a wedge movable on said primary member and coacting

- with said movable jaw, a lever fulcrumed on said primary member and operatively connected to said wedge, means between said movable jaw and wedge whereby said lever 5 may first move said jaw into operative position and thereupon move said wedge relatively to said jaw to grip the latter in said position, and means to lock said movable jaw to said wedge.
- 10 12. A wrench comprising a primary member provided with a jaw, a second jaw movable on said primary member, a wedge movable on said primary member and coacting with said movable jaw, a lever fulcrumed on 15 said primary member and operatively connected to said wedge, means between said movable jaw and wedge whereby said lever may first move said jaw into operative position and thereupon move said wedge relatively to said jaw to grip the latter in said 20 position, and a slidable bolt for locking said movable jaw to said wedge.
13. A wrench comprising relatively-movable hand-operated members, jaws rectilinearly movable relatively to each other by 25 operation of said first-named members, a wedge between one of said jaws and its operating member, and means between said wedge and jaw whereby said wedge is movable 30 with said jaw into operative position and then relatively thereto to grip the same in said position.
14. A wrench comprising relatively pivoted hand-operated members operatively related 35 for manipulation by one hand, relatively movable jaws movable into operative position by relative movement of said hand-operated members, a wedge between one of said jaws and its operating member, and 40 means between said jaw and wedge whereby said wedge is movable with said jaw into operative position and then relatively thereto to grip the same in said position.
15. A wrench comprising relatively-movable 45 hand-operated members, relatively-movable jaws movable into operative position by relative movement of said hand-operated members, and means comprising a wedge between one of said jaws and its operating member for moving said jaw into 50 operative position and then urging the same transversely to said first-named movement to grip said jaw in said position.
16. A wrench comprising relatively movable 55 jaws, relatively-movable hand-operated members for moving said jaws, a wedge between one of said jaws and its operating
- member and operative connections therebetween whereby relative movement of said hand-operated members in the same direction first moves said jaw and wedge as a unit into operative position and then moves said wedge to grip the related jaw in said position. 60
17. A wrench comprising relatively movable jaws, relatively-pivoted hand-operated members and operative connections between said members and jaws for moving said jaws into operative position, said connections comprising means between one of said jaws and its operating member, brought into operation by continued movement of said members after engagement of said jaws with an object, for gripping the related jaw in said position. 65
18. A wrench comprising relatively movable jaws, hand-operated members and operative connections therebetween for moving said jaws into operative position, said connections comprising a wedge coacting with one of said jaws and brought into operation by continued movement of said hand-operated members after engagement of said jaws with an object for gripping the related jaw in said position. 70
19. A wrench comprising a primary member provided with a jaw and a slideway, a second jaw slidable on said way, a lever fulcrumed on said primary member, and means operatively connected to said lever and interposed between said lever and movable jaw, said means comprising members whereby said movable jaw is moved by said lever into operative engagement with an object and then gripped against said way by 80 continued movement of said lever in the same direction. 85
20. A wrench comprising a primary member provided with a jaw, a second jaw movable on said primary member, a lever fulcrumed on said primary member, means operatively connected to said lever and coacting with said movable jaw for gripping said jaw in operative position, and means coacting with said movable jaw for moving the same into operative position upon movement of said lever and for permitting movement of said first-named means to grip said jaw in said position upon continued movement of said lever. 100
- In testimony whereof I have signed this specification. 105
- ISAAC W. LITCHFIELD. 110
